UNITED STATES PATENT OFFICE.

JOHN S. GABKE, OF WILMINGTON, DELAWARE.

TOY VEHICLE.

Application filed June 21, 1921. Serial No. 479,185.

To all whom it may concern:

Be it known that I, JOHN S. GABKE, a citizen of the United States, residing at Wilmington, in the county of New Castle 5 and State of Delaware, have invented certain new and useful Improvements in Toy Vehicles, of which the following is a specification.

One object of my invention is to provide 10 a toy vehicle of novel construction which will afford amusement and healthful exercise for children; said vehicle being so made that it can be easily and conveniently operated.

Another object is to make my improved 15 vehicle of a simple and durable construction which can be easily kept in proper running condition.

These objects, and other advantageous ends 20 which will be described hereinafter, I attain in the following manner, reference being had to the accompanying drawings in which—

Figure 1 is a top plan view of a vehicle 25 made in accordance with my invention; the back portion of the seat being broken away,

Figure 2 is a side elevation of said vehicle,

Figure 3 is a front elevation of said vehicle,

Figure 4 is a rear elevation of the same,

Figure 5 is an enlarged fragmentary top plan view partly broken away,

Figure 6 is a view of the same general 35 character as shown in Figure 5 illustrating the parts having been moved into another position,

Figure 7 is a fragmentary sectional elevation taken on the line 7—7 of Figure 5,

Figures 8 and 9 are fragmentary side elevations showing certain of the parts before and after having been adjusted to take up slack in the driving chain,

Figure 10 is an enlarged section taken on 40 the line 10—10 of Figure 8,

Figure 11 is a section taken on the line 11—11 of Figure 10,

Figure 12 is an enlarged section taken on 45 the line 12—12 of Figure 2, and

Figure 13 is a section taken on the line 50 13—13 of Figure 12.

Referring to the drawings, my improved vehicle includes a main frame 14 which is made of flat strip metal bent within its 55 length to form an elongated loop having side

rails 15 and a curved closed forward end 16. The free ends of the side rails 15 form the rear of the frame and are connected together by a bolt 17 which passes through a tube 18; said tube having its opposite ends 60 abutting the inner opposed surfaces of the side rails 15.

This main frame adjacent its rear has hanger bearings 19 which are made of strip material having loops providing bearings 65 for a rear axle 20. The free ends of the hanger bearings 19 are secured to the respective side rails 15 of the frame 14 as clearly shown in Figures 1, 12 and 13. A

depending looped frame 21, which is made 70 of strip material, has its opposite ends secured to the side rails 15 of the main frame adjacent the end 16. The bottom of this frame 21 has a pivot bolt 22 extending therethrough and through an upwardly extending 75 hood 23; said hood having its ends secured to the front axle 24. This bolt extends through the axle and also through an underhung frame 25; said frame consisting of a

bent piece of strip metal which at its top is 80 connected centrally to a transverse bar 26; this bar being secured to the opposed side rails 15 of the main frame. A spacing pipe or tube 27 surrounds the bolt 22 as shown in Figure 7 and said pipe abuts the lower 85 surface of the axle 24 and the upper surface of the forward end of the underhung frame 25.

Ground-engaging wheels 28 are secured to 90 the rear axle 20 and ground-engaging wheels 29 are freely rotatable on the front axle 24.

A member 30 is secured on the top of the front axle 24 and has its forward end positioned within the confines of the hood 23; 95 said bolt 22 also passing through said member 30. This member 30 has an arcuate portion 31; the inner edge thereof being provided with a row of gear teeth 32 arranged concentric to the axis of the pivot bolt 22.

An auxiliary frame 33 includes a transverse plate portion 34 which extends between the side rails 15 of the main frame and has extensions 35 which are secured to the inner surfaces of said side rails. This plate portion 34 slants downwardly and forwardly 100 and forms an angular or slanting support for a bracket 36; said bracket having end portions 37 and 38 bent at right angles to its slanting body portion 39.

A slanting steering post 40 extends 110

through holes in the portions 37 and 38 of the bracket 36 and has a beveled gear 41 secured thereto which meshes with the teeth 32 of the member 30; said beveled gear extending 5 into the space 42 within the confines of said member 30. A ring washer 43 surrounds the steering post 40 and bears upon the upper surface of the portion 37 of the bracket 36 and I preferably insert a removable pin 44 through the steering post above the ring washer 43 so as to prevent the steering post from moving downwardly. A steering wheel 45 is secured to the post 40 in front of a seat 46; said seat being secured 10 on standards 47 which are attached to the main frame 14.

To hangers 48 are respectively pivoted at 49 to the side rails 15 of the main frame 14. These hangers at their lower ends provide a bearing for a crank shaft 50; said crank shaft at its end portions outside of the hangers 48 having cranks 51 removably secured thereto; said cranks having pedals 52 thereon. The crank shaft 50 has a sprocket wheel 53 secured thereon between the hangers, over which passes an operating chain 54. This chain 54 operatively connects a sprocket wheel 55 which is secured on the rear axle 20 between the hanger bearings 19. Each of the hangers 48 has a block 56 extending laterally therefrom; said block having a stem 57 which is pivotally secured within a hole 58 in the respective hanger 48. The respective blocks 56 have holes through 30 which extends the screw threaded portions 59 of tension rods 60. These tension rods at their upper ends being pivotally secured to the side rails 15 of the main frame 14 at 60^a. Nuts 61 are secured on the portions 35 of the rod 60 and abut the opposite faces of the blocks.

It will be noted that the blocks 56 are positioned below the pivots 49 and in view of the construction above described it will 45 be obvious that by backing off on one of the nuts and turning the other nut further on to the rod, the hanger will be swung forwardly on its pivot 49 and when this adjustment is made on each side of the 50 sprocket 53, the crank shaft 50 will be swung

forwardly so as to take up any slack in the chain 54. Thus during use of the vehicle if the chain 54 becomes slack it is an easy matter to turn the nuts 61 and cause the hangers 48 to be swung on their pivots 49 55 so that the crank shaft 50 will be moved away from the rear axle 40 and the chain 54 can be made taut.

Owing to the construction of the main frame and the mounting of the crank shaft, a child sitting on the seat 46 can readily 60 reach the pedals and by an easy movement of the legs can readily propel the vehicle; the thrust imparted to the crank shaft being resisted by the tension rods 60. Furthermore by constructing the parts as above 65 described they can be quickly and cheaply made and assembled.

While I have described my invention as taking a particular form, it will be understood that the various parts of my invention may be changed without departing from the spirit thereof, and hence I do not limit myself to the precise construction set forth, but consider that I am at liberty to make 70 such changes and alterations as fairly come within the scope of the appended claims.

Having thus described my invention, what I claim as new and desire to secure by Letters Patent is:—

A toy vehicle comprising a frame; an axle mounted on the frame; traction wheels fixed to the axle; a sprocket fixed to the axle; hangers pivoted to the frame; a shaft bearing in the hangers; a sprocket fixed to the 85 shaft between the hangers; a chain connecting the sprockets; blocks pivoted on the hangers; tension rods pivoted on the frame and adjustably connected to the blocks, and means for holding the hangers in an 90 adjusted position against swinging movement in either direction.

In testimony whereof I have signed my name to this specification in the presence of two subscribing witnesses.

JOHN S. GABKE.
